UNITED STATES PATENT OFFICE.

WILLIAM P. YANT, OF PITTSBURGH, PENNSYLVANIA; ROYD R. SAYERS, OF WASHINGTON, DISTRICT OF COLUMBIA; AND JOEL H. HILDEBRAND, OF ALAMEDA, CALIFORNIA.

ARTIFICIAL BREATHING ATMOSPHERE AND TREATMENT OF PERSONS EXPOSED TO ABNORMAL PRESSURES.

No Drawing.

Application filed May 20, 1925. Serial No. 31,690.

This invention relates to artificial atmospheres and the use of the same in treating persons exposed to abnormal pressures and is particularly useful in connection with diving or caisson work.

Notwithstanding the increasing demand for a greater range in deep sea diving and other submarine operations, very limited progress has been made toward materially extending the time limits at which men are enabled to work under the extremely adverse pressure conditions encountered in such operations. It has been attempted to construct diving suits of a non-yielding character so that the man encased therein might work at atmospheric pressure, but these devices, because of mechanical difficulties, clumsiness and lack of freedom of the diver for performing work, have been found generally unsatisfactory. The usual apparatus in which the diver is subjected to an air pressure equal to that of the water at the depth of operation has been found the only practical suit for submarine operations. At the present time the practical working limit is at a depth of about two hundred feet of water. At such pressure the diver is subjected to a pressure of approximately 100 pounds per square inch, or a total body pressure of about 230,000 pounds. This pressure in itself is not harmful since the body builds up an internal balancing pressure principally through the respiratory and circulatory system of the body. The body fluids and tissues act like a liquid which is exposed to gaseous pressure and absorb the gas until a pressure balance is attained. It should be mentioned that a greater time lag occurs, but in this respect only does the body act in any materially different fashion from a liquid under pressure. This building up of pressure within the body can be accomplished with great rapidity and there is little or no physiological danger attendant upon the lowering of the diver to his field of operations, since the body is in a condition of undersaturation.

It has been known for many years, however, that serious difficulties are encountered upon the decompressing operation or the step of raising the diver back to the surface. If the decompression is brought about over too short a time period the diver is subjected to

cramps and the severe acute symptoms known as the bends or caisson worker's disease. If the time is greatly reduced paralysis or death may result. Experiments show that these effects are due to the release of gas bubbles within the body when the reduction of pressure outside the body has been brought about and the body acts like a solution in attempting to dispose of the excess internal pressure. If these gas bubbles occur in the blood vessels they may collect in the heart and the circulation may thus be impaired or stopped. If they occur in the brain or the spinal cord paralysis results.

It has therefore been necessary to use extreme care in decompressing persons who have been exposed to high pressure so that the excess pressure may pass off without the formation of harmful gas bubbles in the body. By the law of partial pressures any gas which goes into solution in the body liquids or tissues will build up an internal pressure to correspond to the external pressure which would be exerted by that same gas alone if it were occupying the space in which the body is confined. Accordingly the internal body pressure during decompression is made up of a component of pressure corresponding to the excess oxygen content of the body and a component corresponding to the excess nitrogen content of the body. The excess oxygen, within a limited pressure range, can be used up by the cells in the body metabolism. The nitrogen, however, must pass off principally, if not entirely, through the lungs and the decompression rate must be so regulated as to prevent the dangerous bubbling effect above described. The permissible decompression rate increases with the depth since the quantity of gas absorbed by the body increases directly with the pressure. For example, the body fluids and tissues when at equilibrium with ten atmospheres pressure will have in solution ten times the volume of gas they would contain at one atmosphere, assuming the fluids and tissues to act as perfect liquids. There is a certain variation from this, but experiments have shown that such conditions are at least approximated in the body. This means that in decompressing from say ten atmospheres, nine times the normal nitrogen content must

be removed. The time required for such decompression from pressures greater than 200 feet of water is found in practice to be so great as compared with the useful work period that diving to greater depths is impractical except in rare emergencies.

We provide an artificial atmosphere, including oxygen and a gas having a greater rate of diffusibility than nitrogen or less soluble in the body than nitrogen, or both. Helium is the preferred gas employed. The diffusion rate of helium is about twice that of nitrogen and its solubility in the body is about one half that of nitrogen. The greater diffusibility of helium is due to its lower molecular weight, the rates of diffusion of gases from liquids varying inversely as the square roots of their molecular weights. Because of its greater diffusibility, the helium, during decompression, passes out of the body about twice as fast as nitrogen. Because of its lesser solubility, only about half as much helium goes into solution in the body tissues as would nitrogen. Therefore, any bubbling which might occur on decompression would be approximately one-fourth as great as that due to nitrogen.

Actual experiments have shown that with an artificial atmosphere of oxygen and helium, the decompression time may be reduced to one fourth or one fifth of that now necessary where ordinary air is used. Because of such reduced decompression time, the field of commercial diving may be extended to depths considerably below those now considered practicable.

The artificial atmosphere may be used throughout the period during which the diver is exposed to the high pressure. It will be seen, however, that in caisson work, the cost of using helium would be very high. The advantages of our invention, however, may be secured by substituting the artificial atmosphere during the decompression period only. As above pointed out, the compression operation is not injurious, since the body is in an undersaturated condition and is merely absorbing the gases. A caisson worker or diver may therefore be compressed in the ordinary manner and work in an atmosphere of oxygen and nitrogen without harm. Then when it is desired to decompress, a mixture consisting of oxygen and helium may be supplied. When this atmosphere is substituted for air, then by the law of partial pressures, the effect on the nitrogen dissolved in the body is that of a nitrogen vacuum, and the nitrogen will rapidly diffuse out of the body. The total pressure, of course, is made up by the partial pressure of the helium which is substituted for the nitrogen, so that bubbling will not occur. During this process, the nitrogen in the body will be replaced to some extent

by the helium which, however, is more rapidly diffusible from the body as the decompression proceeds.

Also, the advantages of our invention may be secured by employing the artificial atmosphere of oxygen and helium, even after the man has been decompressed. It is a well known fact that the "bends" may not occur until some five or six hours after decompression has occurred. When this occurs the subject may be recompressed and then decompressed in an atmosphere of helium and oxygen. This will increase the tendency of the nitrogen to pass out of the body and to prevent the recurrence of harmful bubbling.

While helium is the best gas known to us at the present time for this purpose, other inert, respirable gases which have a greater rate of diffusibility than nitrogen or a lesser solubility in the body than nitrogen, or both, may be employed. For example, hydrogen, which has a very low molecular weight, may be employed, although considerable danger would be attendant upon its use because of its great inflammability. Neon is another gas whose molecular weight is less than that of nitrogen and which might be employed if sufficient quantity were available.

While it is preferred to use an artificial atmosphere consisting principally, if not entirely, of oxygen and helium (or the other inert gas employed), the artificial atmosphere may be made up by diluting ordinary air with helium or the other inert gas, which, as we shall hereinafter point out, has the further effect of preventing oxygen poisoning. Or the artificial atmosphere may consist of oxygen and nitrogen together with helium or the other inert gas. When such mixtures are used, the partial pressure of the nitrogen will be reduced by the admixture of helium, and the advantages of an oxygen-helium atmosphere will be obtained, although of a somewhat impaired degree.

We have also discovered that the so-called oxygen poisoning may be prevented by supplying the diver or caisson worker with an atmosphere containing a reduced proportion of oxygen as compared with the atmospheric air.

Under the smaller pressures encountered in compressed air work, oxygen poisoning is not particularly serious or noticeable, since the body can accommodate itself to a limited increase in concentration of absorbed oxygen. On the other hand, if the pressure is increased say to ten atmospheres, the partial pressure of the oxygen is increased ten times, and the concentration of oxygen in the body may cause oxygen poisoning, particularly if the diver is exposed to it for a considerable period of time. Oxygen poisoning may be prevented by diluting the atmosphere supplied with an inert gas to

lower the proportion of oxygen below that of atmospheric air. The inert gas so supplied, and particularly in the case of a diver where a relatively small quantity is required, 5 is preferably helium, since the helium will not only serve as a diluent, but will serve as an aid to permit more rapid decompression. On the other hand, where large quantities of air are required, as in caisson work, 10 a cheaper diluent may be employed, such, for example, as nitrogen, in order to prevent oxygen poisoning. Where nitrogen is used as a diluent, it is preferred to employ some gas such as helium as an aid in decompression.

The human body can accommodate itself to an oxygen content of from about 15 to 100% at a pressure of one atmosphere. The 20 partial pressure of the oxygen increases directly with the pressure applied to the atmosphere breathed, so that under compression the body may be subjected to an oxygen concentration greater than that of pure oxygen at atmospheric pressure. For example, 25 if atmospheric air be compressed ten times, the body will be subjected to absolute oxygen pressure of about 2.1 atmospheres. Therefore, in making the respirable mixtures for diving or other compressed air work, the oxygen content should be calculated so that the oxygen concentration is within the limits above set forth. For example, if a pressure of ten atmospheres is to be employed, the oxygen content should be 30 between 1.5 and 10% of the volume of the compressed gas. Preferably the oxygen content is between .5 and 1 atmosphere absolute pressure. In practical use of atmospheres containing low percentages of oxygen by 35 volume for high pressure diving or other compressed air work, it is necessary to increase the volume percent of oxygen at the lower transition pressures during compression and decompression.

45 While we have described the preferred ways of carrying out our invention, and particularly as embodied in the use of helium, it is to be understood that the invention is not thus limited but may be otherwise embodied within the scope of the following claims.

We claim:

1. A respiratory atmosphere containing a 55 percentage of oxygen less than that in air, and such that when breathed under supernormal pressures irritation to the respiratory tract or oxygen poisoning will not occur.

2. A respiratory atmosphere composed 60 principally of oxygen and helium, the percentage of oxygen being less than that in air, and such that when breathed under supernormal pressures irritation to the respiratory tract or oxygen poisoning will not occur.

65 3. A respiratory atmosphere composed

principally of oxygen and a gaseous diluent having a lower solubility in body tissues and liquids than nitrogen, the percentage of oxygen being less than that in air, and such that when breathed under supernormal pressures irritation to the respiratory tract or oxygen poisoning will not occur.

4. A respiratory atmosphere composed principally of oxygen and a gaseous diluent having a greater rate of diffusibility than 75 nitrogen, the percentage of oxygen being less than that in air, and such that when breathed under supernormal pressures irritation to the respiratory tract or oxygen poisoning will not occur.

5. A respiratory atmosphere composed principally of oxygen and helium, the percentage of oxygen being less than that in air, and such that the partial pressure of oxygen in the composition will not exceed 1 85 atmosphere absolute pressure when breathed at pressures greater than 75 pounds per square inch absolute.

6. In the treatment of persons exposed to supernormal pressures, the step consisting 90 in supplying to such persons an artificial respiratory atmosphere containing a percentage of oxygen less than that in air, and such that when breathed under supernormal pressures irritation to the respiratory tract 95 or oxygen poisoning will not occur.

7. In the treatment of persons exposed to supernormal pressures, the step consisting 100 in supplying to such persons an artificial respiratory atmosphere composed principally of oxygen helium, the percentage of oxygen being less than that in air, and such that when breathed under supernormal pressures irritation to the respiratory tract or oxygen poisoning will not occur.

8. In the treatment of persons exposed to supernormal pressures, the step consisting 110 in supplying to such persons an artificial respiratory atmosphere composed principally of oxygen and a gaseous diluent having a lower solubility in body tissues and liquids than nitrogen, the percentage of oxygen being less than that in air, and such that when breathed under supernormal pressures irritation to the respiratory tract or 115 oxygen poisoning will not occur.

9. In the treatment of persons exposed to supernormal pressures, the step consisting 120 in supplying to such persons an artificial respiratory atmosphere composed principally of oxygen and a gaseous diluent having a greater rate of diffusibility than nitrogen, the percentage of oxygen being less than that in air, and such that when breathed under supernormal pressures irritation to the respiratory tract or oxygen poisoning will not occur.

10. In the treatment of persons exposed to supernormal pressures, the step consisting 125 in supplying to such persons an artificial

- respiratory atmosphere composed principally of oxygen and helium, the percentage of oxygen being such that the partial pressure of oxygen in the composition will not exceed 1 atmosphere absolute pressure when breathed at pressures greater than 75 pounds per square inch absolute.
11. In the treatment of persons undergoing extreme changes in pressure, the steps which consist in supplying to such persons, while under compression, a respiratory atmosphere composed principally of oxygen and nitrogen, and supplying, while under decompression, a respiratory atmosphere composed principally of oxygen and helium.
12. In the treatment of persons undergoing extreme changes in pressure, the steps which consist in supplying to such persons, while under compression, a respiratory atmosphere composed principally of oxygen and nitrogen, and supplying, while under decompression, a respiratory atmosphere composed principally of oxygen and a gaseous diluent having a lower solubility in body tissues and liquids than nitrogen.
13. In the treatment of persons undergoing extreme changes in pressure, the steps which consist in supplying to such persons, while under compression, a respiratory atmosphere composed principally of oxygen and nitrogen, and supplying, while under decompression, a respiratory atmosphere composed principally of oxygen and a gaseous diluent having a greater rate of diffusibility than nitrogen.
14. In the treatment of persons undergoing extreme changes in pressure, the steps which consist in supplying to such persons, while under compression, a respiratory atmosphere composed principally of oxygen and nitrogen, the percentage of oxygen being less than that in air and such that when breathed under supernormal pressures irritation to the respiratory tract or oxygen poisoning will not occur, and supplying, while under decompression, a respiratory atmosphere composed principally of oxygen and helium.
15. In the treatment of persons undergoing extreme changes in pressure, the steps which consist in supplying to such persons, while under compression, a respiratory atmosphere composed principally of oxygen and nitrogen, the percentage of oxygen being less than that in air and such that when breathed under supernormal pressures irritation to the respiratory tract or oxygen poisoning will not occur, and supplying, while under decompression, a respiratory atmosphere composed principally of oxygen and helium, the percentage of oxygen being less than that in air and such that when breathed under supernormal pressures irritation to the respiratory tract or oxygen poisoning will not occur.
16. In the treatment of persons undergoing extreme changes in pressure, the steps which consist in supplying to such persons, while under compression, a respiratory atmosphere composed principally of oxygen and nitrogen, the percentage of oxygen being less than that in air and such that when breathed under supernormal pressures irritation to the respiratory tract or oxygen poisoning will not occur, and supplying, while under decompression, a respiratory atmosphere composed principally of oxygen and a gaseous diluent having a solubility in body tissues and liquids less than that of nitrogen.
17. In the treatment of persons undergoing extreme changes in pressure, the steps which consist in supplying to such persons, while under compression, a respiratory atmosphere composed principally of oxygen and nitrogen, the percentage of oxygen being less than that in air and such that when breathed under supernormal pressures irritation to the respiratory tract or oxygen poisoning will not occur, and supplying, while under decompression, a respiratory atmosphere composed principally of oxygen and a gaseous diluent having a greater rate of diffusibility than nitrogen.
- In testimony whereof we have hereunto set our hands.
